UNITED STATES PATENT OFFICE.

WALTER S. MCKEE, OF CHICAGO, ILLINOIS, AND FRANK E. JOHNSON, OF SALT LAKE CITY, UTAH, ASSIGNEES, BY MESNE ASSIGNMENTS, TO AMERICAN MANGANESE STEEL COMPANY, OF AUGUSTA, MAINE, A CORPORATION OF MAINE.

CRUSHER JAW-PLATE.

1,187,163.

Specification of Letters Patent. Patented June 13, 1916.

Original application filed January 25, 1915, Serial No. 4,088. Divided and this application filed February 26, 1916. Serial No. 80,564.

To all whom it may concern:

Be it known that we, WALTER S. MCKEE, a citizen of the United States, and a resident of Chicago, in the county of Cook and State of Illinois, and FRANK E. JOHNSON, a citizen of the United States, and a resident of Salt Lake City, in the county of Salt Lake and State of Utah, have made and invented certain new and useful Improvements in Crusher Jaw-Plates, of which the following is a specification.

This invention relates to sectional crusher jaw plates, the object being to so construct the several sections that they may be so locked together as to possess the rigidity and strength of an integral casting.

This application is a division of our co-pending application Ser. No. 4088, filed January 25, 1915.

20 The lowermost portion of a crusher jaw plate is subject to the most rapid wear, and, for this reason, it is of advantage to form the crusher jaw plate in sections. While it is important that the sections may be easily 25 and conveniently removed, it is also essential that the various sections be held in rigid alinement and one section prevented from moving in front or to the side of adjacent sections.

30 With this in view we have provided the ends of each section with interfitting members, whereby each section is adapted to engage and become locked to the adjacent sections, it being among the objects of the present invention to accomplish the above-mentioned ends in a simple, practical and expeditious manner.

Other objects and advantages will appear as the description proceeds, wherein it is to 40 be noted that changes in the precise embodiment of our invention can be made within the scope of what is claimed, without departing from the spirit thereof.

The preferred embodiment of our invention is disclosed in the accompanying drawings, wherein:

Figure 1 is a view in front elevation of our improved crusher jaw plate, portions

of the lower section being broken away; Fig. 2 is a view in side elevation of the foregoing, parts thereof being represented in section; Fig. 3 is a view in horizontal section, taken on the line 3—3 of Fig. 2; Fig. 4 is a view in perspective of one section of the jaw plate; Fig. 5 is a view in side elevation thereof, illustrating the manner in which the interlocking member or lip is removed from the end of the lowermost section prior to its being positioned within the jaw of the crushing machine; Fig. 6 is a view in side elevation and partially in section of a crusher jaw plate, wherein the projecting lip of each section extends from the upper end thereof rather than from the lower end, as in the previous type; Fig. 7 is a view in side elevation of a slightly modified form of jaw plate, the modification residing in the connection between the several sections; Fig. 8 is a view in front elevation and partially in section of a further modified form of the jaw plate, which is illustrated in side elevation in Fig. 9; Figs. 10 and 11 are views in front and side elevation respectively, of a further modified form of connection between the sections of a jaw plate; and Figs. 12 and 13 are views in front and side elevation of a still different form of connection for the several sections.

Referring specifically to the several views, the crusher jaw plate, illustrated in Figs. 1, 2 and 3, is formed of a number of transverse sections 10, 11 and 12, and a top wedge-shaped section 13; the several sections 10, 11 and 12 being identical, are interchangeable, so that the lowermost section, which is subjected to the greatest and most rapid wear, may be discarded after becoming worn beyond use, and the next section thereabove moved downwardly, so as to occupy the position of the discarded section. The formation of the jaw plate in sections renders necessary the secure locking of the several sections together, so as to maintain the various ribs and corrugations of the wearing faces in fixed and proper relation, and to also prevent one section from moving in front

of the adjacent sections. With this in view, we have provided the lower and beveled end 14 of each section with a downwardly projecting lip 15. This lip extends entirely across the lower end of each section and enlarges at its lower extremity to form a rib 16, the one wall 17 of which is undercut or beveled, corresponding to the bevel of the end 14 of the section. The lower wall 18 of the rib extends substantially perpendicular to the plane of the back of the section. The upper end of each section is provided with a recess, corresponding to the outline of the lip 15 and rib 16. The various sections are assembled in their jaw plate forming relation by moving one section transversely to the adjacent section and sliding the lip into the recess of the sub-adjacent section. The connection between the several sections thus positively locks them together except in a transverse direction, and to prevent this movement a beveled key 19 is secured within suitable undercut slots 20, which extend along the back of the several sections, and which align when the sections are in proper place. The lowermost section must fit snugly within the jaw (not shown) of the crushing machine, and, for this reason, it is necessary that the protruding lip 15 of the lowermost section be removed. In order that this may be conveniently accomplished, each section is provided with a transversely extending notch 21, located at the innermost extremity of the lip thereby allowing the lip 35 to be broken away at the proper point for its complete removal.

The crusher jaw plate, illustrated in Fig. 6, is similar to the foregoing, with the exception that the lips 15' project upwardly from the upper end of each section, and the corresponding recesses 18' are formed along the lower end of each section, thus doing away with the necessity of breaking off the lip of the lowermost section before it can be assembled in the crushing machine.

In those instances where it is impractical to assemble the several sections, of the crusher jaw plate, by relative transverse movement, the form of interlocking lips and recesses, illustrated in Fig. 7, are employed. In this type of lip and recess, the lowermost wall 18'' thereof extends substantially parallel to the inner and undercut wall 17'' of the lip and parallel lower end 14' of the section. In this type of jaw plate the several sections are assembled directly one upon the other and the undercut locking key 19' is inserted in place, completing the securement between the several sections. In this connection attention is called to the fact that although the preceding forms of jaw plates have been illustrated with the lips and recesses extending entirely across the sections, this arrange-

ment may be modified, as illustrated in Figs. 10 and 11, wherein the lips and recesses are of limited length and are located at the outer edges of the several sections, or may be formed at the center of the several sections, as illustrated in Figs. 12 and 13, the locking key in these instances being omitted if desired.

A somewhat simpler connection between the several sections is disclosed in Figs. 8 and 9, wherein the lips 25 and recesses 26 partake of the form of the ordinary tongue and groove, and, owing to the fact that the lip 25 is substantially equal in thickness to that of the locking key 27, they do not extend entirely across the back but only up to the sides of the locking key.

The rigid and positive securement between the several sections of the various jaw plates, as above described, prevents the ribs and corrugations of the wearing face from moving out of proper relation as well as holding the sections from moving one in front of the other. The crusher jaw plate, although formed of replaceable sections, possesses the characteristics of an integral casting and may be conveniently handled and transported, as well as easily and quickly secured in place in the jaw of a crushing machine and readily removed therefrom, this latter feature providing for the convenient replacement of a worn section.

What we claim is:—

1. A crusher jaw plate formed of a plurality of sections, and interlocking means extending along the ends of said sections holding them against lengthwise separation and against movement one in front of the other.

2. A crusher jaw plate formed of a plurality of sections, said sections provided along their upper and lower ends with similarly shaped projecting lips and recesses, said lips and recesses adapted to interlock and hold said sections against lengthwise separation.

3. A crusher jaw plate formed of a plurality of interchangeable sections, said sections being provided along their upper and lower ends with similarly shaped, projecting lips and recesses, and a locking member extending longitudinally of said plate, holding the several sections against transverse movement.

4. A crusher jaw plate comprising a plurality of interchangeable wearing sections with the upper and lower ends thereof provided with interlocking similarly shaped projecting lips and recesses, said sections provided with aligned undercut recesses and a beveled key fitting within said aligned recesses and extending longitudinally of said jaw plate and in connection with said lips

and first-mentioned recesses, holding the several sections in fixed relation.

5. A crusher jaw plate formed of a plurality of sections, interengaging means extending along the ends of said sections holding them in proper position, and a locking member extending longitudinally of said sections, holding them against transverse movement.

Signed at Chicago, in the county of Cook

and State of Illinois, this 23 day of February, 1916.
